UNITED STATES PATENT OFFICE.

OLIVER A. QUAYLE, OF ALBANY, NEW YORK.

DESIGN FOR A BADGE.

No. 37,757.

Specification for Design.

Patented Dec. 26, 1905.

Application filed November 6, 1905. Serial No. 286,154. Term of patent 3½ years.

To all whom it may concern:

Be it known that I, OLIVER A. QUAYLE, a citizen of the United States, residing at Albany, in the county of Albany and State of New York, have invented a new, original, and ornamental Design for a Badge, and reference is made to the accompanying drawing, illustrating the same.

The figure is a plan view of a badge, showing the design.

I claim—

The ornamental design for a badge as shown.

OLIVER A. QUAYLE.
